UNITED STATES PATENT OFFICE.

JAMES L. WOODARD, OF OAKLAND, CALIFORNIA.

BUILDING-LUMBER.

1,118,990.

Specification of Letters Patent.

Patented Dec. 1, 1914.

Application filed January 18, 1913. Serial No. 742,867.

To all whom it may concern:

Be it known that I, JAMES L. WOODARD, a citizen of the United States, residing at Oakland, in the county of Alameda and 5 State of California, have invented new and useful Improvements in Building-Lumber, of which the following is a specification.

This invention relates to masonry buildings, and has for its object to provide improved means and method for the erection 10 thereof.

It is an object to provide a ready means for building walls, partitions and floors, also roofs, having the advantages of monolithic 15 construction without requiring the use of molds, and which will be of a simple character such as will not necessitate skilled artisans for its use.

It is an aim to evolve a building lumber, 20 which, without special frame work for its support, may be utilized in conjunction with suitable concrete mixtures for the building of walls, partitions, floors, and the like.

It is a particular aim to enable the utilization 25 of waste products in wood mills, although the invention is also well adapted to be formed in terra cotta and other plastics.

Additional objects and advantages will be 30 apparent from the following description and from the drawings, in which—

Figure 1 is a sectional view of a building constructed in accordance with my invention, Fig. 2 is a fragmentary sectional view 35 showing the angle at the junction of two walls, Fig. 3 is a detail side view of a piece of my lumber, Fig. 4 is an end view thereof, Fig. 5 is a side view of a modification, utilizing 40 small scraps of wood, Fig. 6 is a fragmentary side view of a wall constructed with a further modification of the lumber, partly in section.

There is illustrated a building including 45 the foundation 10, on which a wall 11 is carried, floors 12 and a roof 13 being supported by the wall. There is also a central partition 14 shown.

The foundations are constructed in any 50 suitable manner, and upon these for the outer walls there are laid longitudinally the lumber beams or stringers 15 which are built up from a number of strips 16 of un-

dressed lumber the rough splintery surface of which increases its hold on concrete. The edges are alternately indented or ad- 55 justed to lie inwardly of the edges of the intervening boards or strips 16, on each side, and at the ends, as seen in Figs. 3 and 4. The boards or strips are suitably secured together in each stringer. The thickness of 60 the stringers from edge to edge of the strips may be proportionate to the character of the wall or partition to be constructed.

For small buildings, the stringers are built upon one another over the wall founda- 65 tions to form wall cores, being adapted to be cut and fitted between window frames, as will be apparent. A temporary means may be employed to hold the lumber walls in place until the concrete is applied, which 70 would enable the lumber cores to be built to a more advanced stage than otherwise, and the concrete put on over larger areas. However, it is possible to build up a few feet of the core and then apply the concrete, by 75 which method no temporary supports for the lumber are necessary. Partitions may be built in the same manner if desired, though a series of piers may be utilized for their support in place of a continuous 80 foundation. The walls may also be supported in the same manner. Lighter or narrower stringers may be employed for the partitions than for outer walls. When putting 85 in floors, they may be of the usual construction if desired, the ends of the joists being rested upon the wall cores at the proper height, and the cores built therebetween and continued above, as described.

Or, my stringers may be utilized for the construction of a concrete floor, by extending 90 them across the space between two walls, their staggered edges being presented upwardly and downwardly. Or the lumber may be utilized between I beams, as will be 95 understood without illustration. A roof may be constructed by extending my stringers from the ridge to the tops of walls on opposite sides.

The concrete is applied to the lumber 100 after it has been put in position, by means of a trowel, or other customary methods of like purpose. In this way the lumber may be completely incased on all sides, protect-

ing it from climatic effects, insects, and fire, and when the lumber is used as a roof base, a concrete roof may be easily formed. The formation of the ends of the stringers allows the ready formation of eaves completely incased in concrete, as will be understood.

In Fig. 5 there is shown a modification in which the stringers are formed of boards or strips 16' spaced apart by small blocks 18, which may be spaced in staggered relation, or in alinement transversely of the stringer, suitably spaced from one edge or side, at least. This enables the utilization of small scrap blocks and requires less wood. The first described form of lumber also allows the utilization of short pieces, the junctions of which may be overlapped by adjacent layers.

In Fig. 6 a manner of forming the lumber in terra-cotta blocks is shown. The blocks 17 may be hollow, without any central portion, or may be cellular, whereby their strength is increased. They are formed to present end and side surfaces as nearly like those of the stringers as possible, though they are not essentially the same size and shape. It is deemed important however that the projections 20 and recesses have therebetween the same relative positions and be so arranged as to interlock at their ends, as shown. The projections may be of the dove-tail form on the sides, as has been customary in terracotta lumber, and by forming the end projections and extending the groove 35 22 thus formed through the side projections, the concrete mixture will have ready access to the opposed grooves of the interlocked ends, whereby they will be forcibly secured together. The coengagement of the blocks 40 will be attained, not by the adhesion to the blocks of the cement in the concrete, but by the resistance of the concrete to compressive strain between the opposed faces of the interlocked portions. On this account it may 45 be found desirable to up-end the blocks and let the grooves and rib-like portions extend vertically, or to alternate the arrangement by having a number of courses extend vertically, and then one or two horizontally, 50 whereby the wall would be tied, so to speak, in a way to form a more rigid structure. If desired, blocks may be provided having transversely extending grooves and ribs on their upper and lower faces, adapted to intermesh with those on the ends of the vertically disposed blocks, and one or more of these may be incorporated in the horizontal courses, so that a continuous vertical tie-series of blocks may be formed in a wall. 55 60 It will of course be understood that if desired the projecting portions of the wooden stringers before described may be formed in the same way as shown in the terra cotta form, and the stringers made in short units 65 more or less approximate to blocks.

It should be observed that the grooves on the ends of the blocks are wide enough at their outer part to receive the thickest part of the ribs freely therethrough, where the blocks may be presented longitudinally toward each other for engagement, their use being thus greatly facilitated. The ribs on each side and end are opposed to a groove on the opposite side and end, so that the form of the block is like that of a series of superposed rectangular parallelepipeds of slight altitude and wide bases having their centers arranged in staggered relation in a common plane vertical to their major medial planes and at an angle of forty-five degrees to their 70 75 80 sides.

There is indicated at 26 in Fig. 5 a method of insuring ventilation within the walls, consisting in perforating the lumber so that the spaces 27 will be intercommunicating 85 and dryness and warmth of the building construction materially enhanced.

While in Figs. 3 to 6 of the drawings the stringer units are shown to be each constructed of six layers of planking or blocks, 90 a smaller or larger number of layers may be incorporated in each stringer or unit, if found desirable. It is believed, however, that this is the most practical form for handling and rapid work. The stringers are 95 supplied from the factory in the form shown, each stringer being adapted to rest on another so that the staggered relation of the planks in superposed units will be continuous and uniform, and also so that one 100 end of the stringer may be intermeshed with the side of another when both are laid upon a surface with their tops and bottoms in alinement. By this construction it will be observed that projecting edge portions of 105 the plank are never likely to come into opposition, so that they may be always readily intermeshed. The same is true of the projections shown on the unit in Fig. 6.

What is claimed is:

1. As an improved manufacture, a building lumber unit for cores for walls and the like, comprising a plurality of wooden planks secured together in superposed parallel relation with alternately projecting and inset end and side edge portions whereby to present holding means for concrete, the projections on one side and end being alternated with those on the opposite side and end, whereby they may intermesh with those 115 120 of another unit when the units are alined.

2. A building lumber unit for wall cores and the like having a plurality of sides adapted to snugly fit similar sides of other similar units, said sides each having a plurality of rib-like projections, the projections on opposite sides and ends being staggered, each projection having grooved inner sides and being so spaced relatively as to permit free engagement of like projections of other 125 130

units therebetween, the grooves being disposed so as to aline when the projections are fully intermeshed to form spaces extending medially between the sections and open at each side of the junction, for access of mortar to be compressed by stresses tending to separate the units.

In testimony whereof I have hereunto set my hand in presence of two subscribing witnesses.

JAMES L. WOODARD.
